APPARATUS FOR STACKING FLAT PARTS

Harry Alfandre, Jamaica, N. Y., and Anthony Dominic Iannucci, Waterbury, Conn.; said Iannucci assignor to said Alfandre

Application November 7, 1952, Serial No. 319,238

15 Claims. (Cl. 53—126)

This invention relates to apparatus for stacking flat parts of relatively small dimensions, such as buckles used for straps on ladies' undergarments, and the like.

It is an advantageous practice to string a supply of buckles of this type on a temporary track of any suitable inexpensive strip material, not only for their ready shipment and/or storage, but also for their rapid and correct placement in strap-and-buckle assembly apparatus, such as that shown in Patent No. 2,091,176, dated August 24, 1937, issued in the name of Harry Alfandre.

It is the primary aim and object of the present invention to provide apparatus in which buckles of this type are quickly and automatically stacked so that an attendant need merely slide a temporary track through the aligned apertures in the stacked buckles for their quick mounting on the track.

It is another important object of the present invention to provide the apparatus with a holder in which a plurality of stacks of buckles are simultaneously formed during operation of the apparatus.

It is another important object of the present invention to provide the apparatus with quickly interchangeable holders of the above type, so that empty holders may successively be placed in the apparatus and receive stacked buckles, while an attendant or attendants string the stacked buckles in a loaded holder or holders outside the apparatus onto temporary tracks.

The above and other objects, features and advantages of the present invention will be more fully understood from the following description considered in connection with the accompanying illustrative drawings.

In the drawings:

Fig. 1 is a front elevation of apparatus embodying the present invention;

Figs. 2 and 3 are rear and side elevations, respectively, of the apparatus;

Figs. 4 and 5 are sections taken on the lines 4—4 and 5—5, respectively, of Fig. 1;

Fig. 6 is an enlarged top plan view of a stack holder used in the apparatus;

Fig. 7 is a side elevation of the same stack holder;

Figs. 8 and 9 are sections taken on the lines 8—8 and 9—9, respectively, of Fig. 6;

Fig. 10 perspective illustrates a stack of buckles strung on a temporary track;

Fig. 11 is a fragmentary view of Fig. 9, taken on an enlarged scale, showing one position of the buckles during the stacking operation;

Figs. 12 and 13 are fragmentary views of Fig. 8, taken on an enlarged scale, showing different positions of the buckles during the stacking operation;

Fig. 14 is a rear view of apparatus embodying the present invention in a modified manner;

Fig. 15 is a sectional view taken on the line 15—15 of Fig. 14;

Fig. 16 is a top view of a portion of the apparatus shown in Fig. 14;

2

Fig. 17 is a sectional view, on an enlarged scale, taken on the line 17—17 of Fig. 16;

Fig. 18 is a view similar to Fig. 6 showing a modified form of stack holder;

Fig. 19 is a side elevational view of the stack holder of Fig. 18;

Fig. 20 is a sectional view taken on the line 20—20 of Fig. 18; and

Fig. 21 is a fragmentary end view, taken on an enlarged scale, as viewed in the direction of arrow 21 of Fig. 18.

Referring to the patent drawings, and more particularly to Fig. 10, thereof, there is shown a stack *s* of buckles *b* strung on a temporary track *t*. The instant buckles *b* are of a conventional type having twin apertures and being symmetrical about their longitudinal axes *x*—*x*. Thus, the apertures in the stacked buckles *b* are aligned for the passage of a temporary track *t* through either set of aligned apertures so long as the buckles extend with their longitudinal axes *x*—*x* in the same direction. There are a number of differently shaped and apertured conventional buckles of the same general type as the ones shown herein, such as buckles with single apertures, for instance, all of which lend themselves to ready stringing on temporary tracks if they are stacked with their symmetrical axes extending in the same direction.

Referring now to Figs. 1 to 4, the reference numeral 20 designates any suitably supported base on which is mounted a frame composed of opposite side walls 22 and 24 and a rear wall 26. Mounted on the rear wall 26 and side walls 22 and 24, as by angles 28 and 30, respectively, is an inclined platform 32. Movable on the platform 32 is a slide 34 which carries at its top a plate support 36 for a stack holder 38. The slide 34 may consist of two spaced sections of wood or any other suitable material (Fig. 1). The plate support 36 is provided with a depending lug 40 (Figs. 4 and 5) to which is pivotally connected at 42 a link 44, threadedly received by the shank 46 of a follower 48 on an eccentric 50 which is mounted on a shaft 52 that is journaled in suitable bearing brackets 54 on the rear wall 26 (Fig. 2). The shank 46 of the follower 48 extends through an aperture 56 in the rear wall 26. The shaft 52 carries at one end a pulley 58 which through a belt 60 may be driven from any suitable prime mover, such as an electric motor (not shown).

Mounted at 78 on the forwardly bent ends 70 of suitably mounted upright posts 72 in back of the rear wall 26 is a hopper 74 which is adapted to hold a supply 50 S of buckles *b* (Fig. 5). Hinged at 80 to the rear wall 82 of the hopper 74 is a buckle discharge gate 84 which resembles a scoop, having a bottom wall 86, a rear wall 88 and opposite side walls 90 (Fig. 5). The discharge gate 84 rests on an arm 92 which is pivotally mounted at 94 on a bracket 96 on the rear wall 26 and carries an anti-friction roller 98 that rides on the follower 48 on the eccentric 50. The stroke of the eccentric 50 is relatively short and the latter is driven at relatively high speed, with the result that the slide 34 and plate support 36 are rapidly vibrated on the platform 32 in a direction to and from the rear wall 26, while rapid oscillatory movements of relatively small amplitude are imparted to the discharge gate 84.

It will be noted from Fig. 5 that the portion 85 of the bottom 86 of the discharge gate 84 directly beneath the discharge end 100 of the hopper 74 slopes less than the remaining part of the bottom 86. With this arrangement, a certain predetermined average number of buckles *b* will, during a predetermined time period and during oscillation of the discharge gate 84, be permitted to leave the hopper 74 through the opening 104 in the front

wall 106 of the latter (Fig. 5). Once discharged from the hopper 74 through the opening 104 therein, the buckles *b* will pass quickly to the discharge end of the oscillated gate 84 and gravitate onto the holder 38 in which they become stacked in a manner described hereinafter.

The average amount of buckles *b* released from the hopper 74 during a predetermined time period may be varied by raising and lowering the discharge gate 84 by means of a nut 110 on a threaded rod 112, which is pivotally connected at 114 with the discharge gate 84 and passes through an angle 116 on the front wall 106 of the hopper 74. In Fig. 5, the discharge gate 84 is shown adjusted for oscillatory movement of maximum amplitude. Oscillatory movement of smaller amplitude of the discharge gate 84 is readily attained by taking up on the nut 110, in which case the discharge gate 84 is oscillated through a part only of each stroke of the eccentric 50, as will be readily understood.

Referring now to Figs. 6 to 9, inclusive, there is shown the stack holder 38, which comprises a board 120 having on its front face 122 a plurality of equally spaced, forwardly extending ribs 124 that define individual magazines 126, each for the reception of a stack *s* of buckles *b* (Fig. 8). The board 120 may be made from any suitable material, such as wood or plastic, and the ribs 124 are preferably formed integral therewith (Fig. 9). The board 120 is preferably also provided at its side margins with raised ledges 128 on which to support a transparent, preferably plastic, gate 130 which is adapted to cover the open fronts of the individual buckle magazines or channels 126 in the board 120 (Fig. 9). The gate 130, which is removable from the board 120 for a reason described hereinafter, is provided with a lateral extension 132 with which to engage the bottom surface 134 of the board 120 for the correct location of the gate on the latter. Conveniently, the board 120 is provided on its opposite sides with angles 136 and 138, respectively, which serve as a guideway in which to slide the gate 130 into and from position on the board 120. The board 120 is preferably provided on its back with a projecting lug 140 by means of which to locate the holder 38 on the plate support 36 (Fig. 5). To this end, the plate support 36 is provided with a slot 142 in which the lug 140 fits. The lug 140 is preferably tapered as at 144 to facilitate quick registry of the latter with the slot 142 on placement of the holder 38 on the plate support 36.

The stack holder 38 is further releasably held in place on the plate support 36 by means of a spring member 150 on an angle 152 which is secured at 154 to the plate support 36 (Fig. 5). The spring member 150 is forced into firm holding engagement with a placed holder 38 on the plate support 36 by means of an eccentric 156 on a stub shaft 158, which is journaled in suitable bearing brackets 160 on the angle 152 (see also Fig. 1). The stub shaft 158 is provided with a convenient handle 162 for turning the eccentric 156. For removal of the holder 38 from the plate support 36, the eccentric 156 is turned to a position in which the spring member 150 is released from the holder 38, whereupon the latter is simply lifted from the plate support 36, as will be readily understood.

The bottoms 123 of the channels or magazines 126 are of arcuate configuration and provide longitudinally extending fillet or corner portions 125 which are adapted to support the buckles *b* which slide in the magazines in flatwise disposition, as best shown in Fig. 11. The width of the buckles *b* is slightly less than the width of the magazines or channels 126 and the length of said buckles is preferably slightly less than the height of said channels. From the above it will be apparent that the buckles *b* which slide down the bottoms 123 of the magazines 126 will be supported at the corner portions 125 of said bottoms or bottom walls so as to space

said buckles from said bottoms between the buckle support points defined by the corner portions 125 of the bottom walls of the channels. Thus the buckles *b* when disposed in flatwise disposition on the bottoms 123 of channels 126 are in contact only at the corner portions 125 of said bottoms and defines the space *c* between said buckles and the bottoms 123 of the magazines or channels 126. As previously noted the length of the buckles *b* is slightly less than the height of the channels 126 so that in the stacked condition of said buckles there will be some clearance between the upper ends *e* of said buckles and the bottom face 127 of the gate 130. The ribs 124 of the stack holder 38 are preferably made relatively narrow consistent with structural rigidity in order to minimize the possibility of jamming of the buckles *b* at the entrance to the magazines 126. On placing the holder 38 on the plate support 36 as shown in Fig. 5, and starting the apparatus the buckles *b* will be released from the hopper 74 and will gravitate onto the board 120 of said holder to the entrance of all the magazines 126 therein (Figs. 1 and 5). The buckles *b* will be sufficiently agitated on the vibrating board 120 by the means aforescribed to find their way into the magazines 126 where they will become stacked in a certain disposition in the manner now to be described in detail.

With reference to Figs. 11-13, it will be noted that the buckles *b* will slide down the channels 126 in face-down disposition towards the lower end of said channels. Substantially all of the buckles are forced into stacked disposition at the lower end of each channel through a mutual wedging action which results from the fact that substantially all of the buckles *b* of any one channel slide underneath each other as shown in Figs. 12 and 13 to thereby gradually force the leading buckles into erect disposition progressively. As previously noted there will be a space *c* defined between the bottoms 123 of the channels and the buckles *b* in face-down disposition and this space permits the buckles of a series to slide underneath each other to provide the aforesaid mutual wedging action. It will be understood that during this operation the holder 38 will be vibrated and space *c* will permit a rocking action of the buckles *b* relative to their longitudinal axes, for example buckle *b*₁ will be forced into the disposition shown in Fig. 12 in the manner aforescribed whereby the next adjacent buckle *b*₂ will partially slide underneath buckle *b*₁ and the further continual operation of the apparatus will be effective to force all of the buckles *b* in the stack into an erect disposition. It is possible that one or more buckles in a channel will be oppositely disposed as indicated at *b*₃ in Fig. 13 and such buckles which are thus misarranged simply space the correctly stacked buckles in each of the channels. Thus, as shown in Fig. 13, the misarranged buckle *b*₃ merely spaces stacks *s* and *s'*, the correctly stacked buckles being strung on a temporary track in the manner previously noted. From the above therefore it will be seen that once in the magazines 126, the buckles *b* slide in face-down disposition towards the bottom of the magazines due to the inclination of the agitated holder 38, which is inclined to a horizontal plane preferably less than 45 degrees as shown on the drawings. The consecutive buckles *b* in each magazine 126 crowd each other and become stacked by the above described mutual wedging action which is induced by the vibration of the stack holder 38. It is of paramount importance that the bottoms 123 of channels 126 be so related relative to the flat buckles *b* as to define a space *c* therebetween when said buckles are in a face-down disposition so that when said buckles are in said disposition they may be permitted to rock relative to their longitudinal axes so that adjacent buckles may slide underneath each other to provide the mutual wedging action which ultimately results in the stacking of the buckles *b* in erect disposition as indicated by the stack *s* shown in Figs. 8 and 13.

When the magazines 126 are filled so as to hold complete buckle stacks *s*, the apparatus is stopped and the loaded holder 38 is removed from the latter by an attendant who thereupon removes the gate 130 from the board 120 to expose the stacked buckles in the magazine and permit their being strung on temporary tracks by simply passing the latter through aligned apertures in the several buckle stacks while they are still in their respective channels 126. The strung buckles are preferably held against removal from their temporary tracks by simply driving conventional staples (not shown) into the projecting ends of the tracks. Accordingly, the temporary tracks are preferably made from readily piercable material which moreover provides for the ready release of the buckles from the tracks by cutting the projecting ends thereof. In practice, there are provided interchangeable stack holders 38 which may be used alternately in the apparatus, permitting thereby continuous operation of the latter except while interchanging these holders in the apparatus, while an attendant may devote most of his or her time to string the stacked buckles *b* in the holder or holders removed from the apparatus. While double apertured buckles *b* have been illustrated in the instant embodiment, it will be understood that the instant apparatus readily lends itself to differently shaped and apertured conventional buckles of the same general character as buckle *b*.

With reference to Figs. 14-17, there is shown a modified form of apparatus 170 which is similar to the apparatus previously described except in the respects to be hereinafter pointed out in detail. The apparatus 170 is provided with a hopper 172 which is adapted to contain a supply of buckles *b*. The hopper 172 is of the fixed type and is not provided with a vibrating or agitating discharge gate as in the case of the hopper 74. The rear wall 174 of the hopper 172 is secured to one end 176 of an upright support 178 in any suitable manner, the opposite end 180 of said support being bolted or otherwise secured to the base member 182. The base member 182 is supported by the rear vertical wall 184 which is structurally similar to the rear wall 26 of the previously described embodiment. Thus the hopper 172 is mounted in fixed relation relative to the wall 184 and is not adapted to be vibrated. A base 186 is suitably secured to the support member 182 in any desired manner and said base is adapted to mount the vibratory feeder 188 which is preferably of the well-known "Syntron" type. The "Syntron" vibratory feeder 188 will not be described in detail as such a feeder is conventional and well known, and forms no part of the present invention. The vibratory feeder 188 is provided with a vibrating trough 190 which is adapted to receive the buckles *b* contained in the hopper 172. The vibrating trough 190 has a substantially level base wall 192, which receives the buckles *b* discharged from the hopper 172, side walls 193 and a rear wall 195. Thus the vibrating trough 190 is of scoop-like formation with the base wall 192 thereof being positioned so as to receive the discharged buckles from the hopper 172, it being noted that said trough is spaced from the hopper 172 and is not in contact with anything rigid. The vibratory feeder 188 is further mounted on the base 186 through the intermediation of conventional vibration dampeners so that the vibrations produced by said vibratory feeder is not transmitted to the base 186 and associated structure. The vibrating trough 190 is further provided with an inclined discharge chute 194 which has a base wall 196 which form a continuation of the base wall 192 of the trough 190. The discharge chute 194 is adapted to receive the buckles *b* from the base wall 192 of the vibrating trough 190 and is adapted to direct such buckles onto the stack holder 38'. The discharge chute 194 is provided with a series of spaced vanes or ribs 198 which define the guideways or passages 200 which are adapted to receive the buckles *b* from the hopper 172 and discharge them onto the stack holder 38'. The ribs 198 are divergently arranged on chute 194 so as to evenly disperse the buckles

b from the hopper 172 onto the stack holder 38'. It will be understood that the discharge chute 194 may be dispensed with if desired, in which case trough 190 will be arranged to discharge the buckles directly onto the holder 38, and the sole function of said chute is to distribute in diverging paths the buckles *b* from the hopper 172 to all of the channels 126' of the holder 38'. The vibratory feeder 188 is provided with a variable control of the rate of flow, as is conventional in apparatus of this character, whereby the rate of flow of the buckles *b* from the hopper 172 to the holder 38' may be varied. The mechanism for vibrating the stack holder 38' is substantially identical with the mechanism for vibrating holder 38 of the previously described embodiment. Thus the basic structural distinctions between the apparatus 170 and the previously described embodiment resides in fixedly mounting the entire hopper 172 of apparatus 170 and providing a vibratory feeder 188 for feeding the buckles from the hopper to the stack holder in apparatus 170.

With reference to Figs. 18-21, the stacking board 38' of apparatus 170 is substantially the same as stacking board 38 except in the structural details now to be specifically described. The stacking board 38' is provided with ribs 124' which are structurally similar to ribs 124 of board 38. The ribs 124' are however provided with relatively short extensions 124'', the latter being substantially shorter in height than the ribs 124', said extensions having their ends 125 tapered in the manner shown in Fig. 18 so as to constitute directing means for the buckles *b* positioned on the flat portion 202 and entering the space defined by the extensions 124''. The board 38' is further provided with a removable rod 204 which is adapted to be relatively loosely supported by the screweyes 206 which are secured to the board 38'. The rod 204 is adapted to extend transversely of the board for substantially the full width thereof in the region of and directly above the extensions 124'', as best shown in Fig. 21. The rod 204 is vertically spaced above the extensions 124'' a small amount and constitutes means to limit or restrict the number of buckles *b* entering the channels 126' at any one time. Accordingly the transversely extending rod 204 in conjunction with the rib extensions 124'' constitutes directing structure which serves to guide the buckles into the channels and further prevents an excessive number of buckles *b* from entering the channels 126' at one time. From the above it will be apparent that the board 38' is structurally similar to the board 38 aforementioned except that board 38' is provided with the rib extensions 124'' and the removable rod 204. The apparatus 170 and its associated stacking board 38' function in the manner previously described in detail to stack the buckles *b* in the channels 126' in erect disposition. It will be evident that stacking boards 38 and 38' may be used interchangeably and that board 38' may be used in the first described embodiment.

While we have shown and described the preferred embodiments of my invention, it will be understood that various changes may be made in the present invention without departing from the underlying idea or principles 60 of the invention within the scope of the appended claims.

Having thus described our invention, what we claim and desire to secure by Letters Patent is:

1. Apparatus for stacking identical flat parts in face-to-face vertical disposition, comprising support means having an apertured supporting surface and being vibratory in an inclined plane in the direction of the inclination, a magazine resting on said supporting surface and having a projection receivable in the aperture in said surface, said magazine longitudinally extending in the direction of vibration of said support means and having a longitudinally extending channel closed at its lower end and being throughout of slightly greater width than any of said flat parts, the bottom of said channel having 70 raised corner portions so that portions of said flat parts

will be spaced from the bottom of said channel when said flat parts are positioned face down therein, said channel being open at its upper end for the reception of said flat parts, means for introducing the flat parts to the channel in horizontal, face-down position therein, a manually operable clamp carried by said support means and engageable with the bottom of said magazine for clamping said projection laterally in said aperture, and means for vibrating said support means for concomitantly vibrating said magazine in the direction of said inclined plane.

2. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel being transversely concave so that portions of said flat parts will be spaced from the bottom of said channel when said flat parts are positioned face down therein, said channel being open at its upper end for the reception of said flat parts, means for introducing the flat parts to the channel in horizontal, face-down position therein, and means for longitudinally vibrating said magazine, said last mentioned means comprising an eccentric rotatable about an axis at right angles to the direction of vibration of said magazine, a driving link between said eccentric and magazine, and means for driving said eccentric.

3. Apparatus for stacking identical flat parts in face-to-face vertical disposition, comprising a stacking board having a plurality of upright ribs defining therebetween a plurality of magazines, said stacking board being longitudinally vibratory in an inclined plane in the direction of the inclination, each of said magazines having a longitudinally extending channel closed at its lower end and being throughout of slightly greater width than any of said flat parts, the bottom of said channels being of generally arcuate configuration so that portions of said flat parts will be spaced from the bottom of said channels when said flat parts are positioned face down therein, said channels being open at their upper ends for the reception of said flat parts, means for introducing the flat parts to the channel in horizontal, face-down position therein, and means for longitudinally vibrating said stacking board, whereby said face-down flat parts will slide down said channels towards the lower end thereof into overlapping dispositions and be progressively urged into stacked vertical disposition through a mutual wedging action.

4. Apparatus for stacking identical flat parts in face-to-face vertical disposition, comprising a stacking board having a plurality of longitudinally extending upright ribs defining therebetween a plurality of magazines, said ribs being shorter than the length of said board whereby the latter is provided with an end portion having a surface thereof in communication with said magazines, said stacking board being longitudinally vibratory in an inclined plane in the direction of the inclination, each of said magazines having a longitudinally extending channel closed at its lower end and being throughout of slightly greater width than any of said flat parts, the bottom of said channels being of generally arcuate configuration so that portions of said flat parts will be spaced from the bottom of said channels when said flat parts are positioned face down therein, said channels being open at their upper ends for the reception of said flat parts, said board end portion being adapted to receive said flat parts and direct the latter into said channels in horizontal face-down position, and means for longitudinally vibrating said stacking board.

5. Apparatus for stacking identical flat parts in face-to-face vertical disposition, comprising a stacking board having a plurality of longitudinally extending upright

ribs defining therebetween a plurality of magazines, said ribs being shorter than the length of said board whereby the latter is provided with an end portion having a surface thereof in communication with said magazines, said 5 stacking board being longitudinally vibratory in an inclined plane in the direction of the inclination, each of said magazines having a longitudinally extending channel closed at its lower end and being throughout of slightly greater width than any of said flat parts, the bottom of said channels being of generally arcuate configuration so that portions of said flat parts will be spaced from the bottom of said channels when said flat parts are positioned face down therein, said channels being open at its upper end for the reception of said flat parts, said 10 ribs having a substantially flat longitudinally extending upper edge, a removable cover disposed above said channels and having lower face portions thereof adapted to lie closely adjacent to said flat edges of said ribs whereby said channels will be closed except at said upper ends, said board end portion being adapted to receive said flat parts and direct the latter into said channels in horizontal face-down position, and means for longitudinally vibrating said stacking board.

6. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised corner portions so that portions of said flat parts will be spaced from the bottom of said channel when said flat parts are positioned face down therein, said channel being open at its upper end for the reception of said flat parts, said magazine having an extension portion, the upper face of the latter being in alignment with the bottom of said channel, said face of said extension portion being adapted to receive said flat parts and direct the latter into said channels in horizontal face-down position, a hopper above 25 said magazine adapted to hold a supply of flat parts and being open at the bottom, a pivoted scoop-like discharge gate at the bottom of said hopper, means for vibrating said magazine in its direction of reciprocation, said means simultaneously oscillating said gate to shake parts from said hopper and drop them on said magazine extension portion.

7. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised corner portions so that portions of said flat parts will be spaced from the bottom of said channel when said flat parts are positioned face down therein, said channel being open at its upper end for the reception of said flat parts, said magazine having an extension portion, the upper face of the latter being in alignment with the bottom of said channel, said 30 face of said extension portion being adapted to receive said flat parts and direct the latter into said channels in horizontal face-down position, a hopper above said magazine adapted to hold a supply of flat parts and being open at the bottom, a pivoted scoop-like discharge gate at the bottom of said hopper, an eccentric rotatable about an axis extending at right angles to the direction of reciprocation of said magazine in a plane substantially parallel to that in which the pivot axis of said discharge gate lies, an operating link between said eccentric and magazine, a follower which cooperates with said eccentric and on which said gate rests remotely from its pivot axis to be oscillated thereby for shaking parts from said hopper and drop them on said magazine extension portion, and means for driving said eccentric.

8. Apparatus for stacking identical flat parts, in face-to-

face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised corner portions so that portions of said flat parts will be spaced from the bottom of said channel when said flat parts are positioned face down therein, said channel being open at its upper end for the reception of said flat parts, said magazine having an extension portion, the upper face of the latter being in alignment with the bottom of said channel, said face of said extension portion being adapted to receive said flat parts and direct the latter into said channel in horizontal face-down position, a hopper above said magazine adapted to hold a supply of flat parts and being open at the bottom, a pivoted scoop-like discharge gate at the bottom of said hopper, an eccentric rotatable about an axis extending at right angles to the direction of reciprocation of said magazine in a plane substantially parallel to that in which the pivot axis of said discharge gate lies, an operating link between said eccentric and magazine, a follower which cooperates with said eccentric and on which said gate rests remotely from its pivot axis to be oscillated thereby for shaking parts from said hopper and drop them on said magazine extension portion, means for driving said eccentric, a stop adjustable into positions in which said gate will become seated thereon during a part of each revolution of said eccentric, thereby to shorten the amplitude of the oscillation of said gate.

9. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channels having raised corner portions so that portions of said flat parts will be spaced from the bottom of said channel when said flat parts are positioned face down therein, said channel being open at its upper end for the reception of said flat parts, said magazine having an extension portion, the upper face of the latter being in alignment with the bottom of said channel, said face of said extension portion being adapted to receive said flat parts and direct the latter into said channels in horizontal face-down position, a fixed hopper disposed above said magazine and adapted to hold a supply of flat parts, said hopper being open at the bottom, a vibratory receptacle disposed below the open bottom of said hopper and above said magazine extension portion, said receptacle being adapted to receive said flat parts from said hopper and drop them on said magazine extension portion for stacking in said magazine, and means for simultaneously vibrating said magazine and said receptacle.

10. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised longitudinally extending corner formations defining a depressed portion extending longitudinally and medially of said channel whereby portions of said flat parts will be spaced from the bottom of said channel when said flat parts are positioned face down therein, said channel being open at its upper end for the reception of said flat parts in face-down disposition, and means for longitudinally vibrating said magazine, whereby said face-down flat parts will slide down said channel towards the lower end thereof into overlapping dispositions and be progressively urged into stacked vertical disposition through a mutual wedging action.

11. Apparatus for stacking identical flat parts in face-to-face vertical disposition, comprising a magazine longitudi-

nally vibratory in an inclined plane in the direction of the inclination, said magazine having a longitudinally extending channel closed at its lower end and being throughout of slightly greater width than any of said flat parts, the bottom of said channel being transversely concave whereby portions of said flat parts will be spaced from the bottom of said channel when said flat parts are positioned face-down therein, said channel being of a depth at least equal to the length of any of said flat parts with said channel being open at its upper end for the reception of said flat parts in face-down disposition, and means for longitudinally vibrating said magazine, whereby said face-down flat parts will slide down said channel towards the lower end thereof into overlapping dispositions and be progressively urged into stacked vertical disposition through a mutual wedging action.

12. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised longitudinally extending corner formations defining a depressed portion extending longitudinally and medially of said channel whereby portions of said flat parts will be spaced from the bottom of said channel when said flat parts are positioned face-down therein, said channel being open at its upper end for the reception of said flat parts in face-down disposition, said magazine being inclined less than 45 degrees to a horizontal plane, and means for longitudinally vibrating said magazine, whereby said face-down flat parts will slide down said channel towards the lower end thereof into overlapping dispositions and be progressively urged into stacked vertical disposition through a mutual wedging action.

13. Apparatus for stacking identical flat parts in face-to-face vertical disposition, comprising support means reciprocable in an inclined plane in the direction of the inclination, a magazine releasably carried by said support means and longitudinally extending in the direction of reciprocation of the latter, said magazine having a longitudinally extending channel closed at its lower end and being throughout of slightly greater width than any of said flat parts, the bottom of said channel having raised longitudinally extending corner formations defining a depressed portion extending longitudinally and medially of said channel whereby portions of said flat parts will be spaced from the bottom of said channel when said flat parts are positioned face-down therein, said channel being open at its upper end for the reception of said flat parts in face-down disposition, and means for longitudinally vibrating said support means for concomitantly vibrating said magazine.

14. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel having raised longitudinally extending corner formations defining a depressed portion extending longitudinally and medially of said channel whereby portions of said flat parts will be spaced from the bottom of said channel when said flat parts are positioned face-down therein, said channel being open at its upper end for the reception of said flat parts in face-down disposition, said magazine having an extension portion, the upper face of the latter being in alignment with the bottom of said channel, said face of said extension portion being adapted to receive said flat parts and direct the latter into said channels in horizontal face-down position, and means for longitudinally vibrating said magazine.

15. Apparatus for stacking identical flat parts in face-to-face vertical disposition, comprising a magazine longitudinally vibratory in an inclined plane in the direction of the inclination, said magazine having a longitudinally extending channel closed at its lower end and being throughout of slightly greater width than any of said flat parts, the bottom of said channel being transversely concave whereby portions of said flat parts will be spaced from the bottom of said channel when said flat parts are positioned face-down therein, said channel being of a depth at least equal to the length of any of said flat parts with said channel being open at its upper end for the reception of said flat parts in face-down disposition, a removable cover disposed above said channel for closing the latter at the top thereof, and means for longitudinally vibrating said magazine. 15
